(57) **CLAIM**

The ornamental design for a drop foot brace, as shown and described.

DESCRIPTION

FIG. 1 is a perspective view of a drop foot brace showing my design in a state of use;

FIG. 2 is a front perspective view of the drop foot brace in an open configuration;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a front perspective view of the drop foot brace in a closed configuration;

FIG. 11 is a rear bottom perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is an enlarged detail view of area 18 in FIG. 2 thereof;

FIG. 19 is an enlarged detail view of area 19 in FIG. 3 thereof; and,

FIG. 20 is an enlarged detail view of area 20 in FIG. 4.

The short dash lines in the drawings depict environmental subject matter and form no part of the claimed design.

The dot dot dash lines in the drawings depict the boundaries of the enlarged views and form no part of the claimed design.

The dash lines in a small circular form on the front and back of the article in FIGS. 2-5, 10-12, and 14 depict portions of the drop foot brace that form no part of the claimed design.

1 Claim, 20 Drawing Sheets
